UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed October 16, 1925. Serial No. 62,762.

To all whom it may concern:

Be it known that I, HARRY A. DAVIS, a citizen of the United States, and a resident of Hopedale, in the county of Worcester 5 and State of Massachusetts, have invented an Improvement in Warp Stop Mechanisms for Looms, of which the following description, in connection with the accompanying drawings, is a specification, like characters 10 on the drawings representing like parts.

This invention relates to warp stop mechanisms for looms whereby the loom is brought to rest on the occurrence of a warp fault.

15 Warp stop mechanisms as now ordinarily employed contain a series of drop wires which are normally supported by the warp threads during weaving and when a warp thread becomes broken or too slack for weaving purposes, the associated drop wire acts through a vibrator to effect loom stoppage, that the warp fault may be corrected.

In the correction of the warp fault, it is necessary that the weaver ascertain the location 25 of the broken or too slack warp thread, and in case the warp stop mechanism comprises two or more rows or banks of drop wires, much delay and uncertainty results in locating the bank of drop wires in which 30 the warp fault has occurred, and one of the objects of the present invention is to provide a warp stop mechanism with indicating means for indicating the bank of drop wires where the warp fault has taken place. Usually 35 the weaver runs his hands over the drop wires of the several banks to locate the fallen drop wire, but in accordance with the present invention, means are provided to indicate at once the bank of drop wires 40 containing the broken or too slack thread.

Another important feature of the invention is to provide a warp stop mechanism which shall be simple in construction and wherein any one of the vibrators of the 45 several banks of drop wires may be stopped by a fallen drop wire while the others remain in action until the loom is finally brought to rest.

The invention, novel features and new 50 combination of parts will best be made clear from the following description and the accompanying drawings of one good form thereof.

In the drawings:

55 Fig. 1 is a side elevation of sufficient

portions of a loom containing the present invention to make clear the construction and mode of operation thereof;

Fig. 2 is an end elevation, partly in section, of the main portions of the warp stop 60 mechanism, showing one of the drop wires in its lowered position;

Fig. 3 is a perspective view at one end of the warp stop mechanism; and

Fig. 4 is a side elevation of the parts 65 indicated in Fig. 3 with one of the drop wires shown in dotted lines in its loom stopping position.

The advantages of the present invention are best manifested in a warp stop mechanism of that type wherein a vibrator is associated with each bank of drop wires and is given its oscillating detecting movement during weaving. In this type of warp stop mechanisms the vibrators of the several 70 banks of drop wires pass through openings of the drop wires which have wide and narrow portions, so that the vibrator may freely partake of its oscillating detecting movement in the wider portion of the opening 75 and when any one of the drop wires of the bank is released by its warp thread, the vibrator may be arrested by the narrower portion of the opening, to effect loom stoppage. The train of mechanism between the warp 80 stop mechanism and the loom stopping device may be variously contrived, but as indicated in Fig. 1, such train of mechanism is made effective to stop the loom by a shipper knock-off when a warp thread becomes 85 broken or too slack for weaving purposes.

The loom frame 1 may be of usual construction and supports the warp beam 2 from which the warp threads *a* are led 90 from the rear towards the front of the loom. Mounted on the loom frame is the lay 3, having the lay swords supported for rocking movement, and connected to the lay is a bunter 5 which, in the present instance 100 of the invention is caused to engage a dog 6 as the lay moves back, when such dog is moved into the path of the bunter on the occurrence of a warp fault. The dog 6 and its connection 7 with the shipper knock-off 8, the flexible sheathed wire 9 extending between the warp stop mechanism proper and the dog 6 for operatively positioning the dog 105 on the occurrence of a warp fault, may all be substantially of the same general char- 110

acter as shown and described in the patent to Louis S. Burbank, No. 1,240,666, September 18, 1917, and as such train of mechanism may be varied in connection with the actual 5 invention as herein described, further description of these details will be unnecessary.

The warp stop mechanism proper comprises the bracket 10, one at each side of the 10 loom, which may be conveniently supported by posts 11 which pass through a sleeve 12 on each of the brackets.

Extending between similar bearings 13 formed on the opposite brackets 10 are the 15 warp supporting bars 14 on which the warp threads *a* rest during normal weaving operation.

The drop wires 15 have openings 16, the 20 top portion of the opening being narrowed at 17, and through each bank of drop wires 25 extends a vibrator 18 which is of non-circular cross-section, as indicated in Fig. 2. In the present instance of the invention, the drop wires 15 are arranged in four banks, and with each bank is associated a vibrator 18 which has free oscillatory movement in the wide portions of the slots 16 of the drop wires during weaving. The drop wires 15 are supported by the warp threads *a* during 30 normal weaving operation, but should any 35 one of the warp threads break or become too slack for weaving purposes, the associated drop wire will fall and by engagement with the narrow portion 17 of the slot in the drop wire, arrest the oscillating movement 40 of the associated vibrator.

Mounted for rocking movement in the 45 bracket 10 are the sleeves 19 having secured to each a vibrator 18. Such connection may be made by forming an opening 50 in the end of the sleeve 19 of the same or substantially the same cross-sectional shape as the associated vibrator 18, the construction being such that should the rocking sleeves 19 be rocked or turned, they will impart similar movement to each of the associated vibrators, it being understood that each vibrator 18 has an associated rocking sleeve 19. On the outer end of the sleeve 19 is a cam 20.

Extending between the upright portions 55 21 and 22 of the bracket 10 are a series of rock shafts 23, the outer end portions of which project beyond the outer surface of the portion 21 of the bracket, and are there 60 connected to an arm 24, all of which are united to a bar 25, Fig. 3, whereby the rock shafts 23 (of which there are the same number as vibrators 18) are given a simultaneous rocking movement. The inner ends of each 65 of the rock shafts 23 extend into a hollow portion of the rocking sleeve 19, as indicated in Fig. 4, to thereby provide for the inner ends of each rock shaft a rocking bearing. Such rocking movement may be 70 given to the vibrators by any suitable means

driven from a going part of the loom, as usual, and in the present instance, one of the arms 24 is provided with an extension 26, Fig. 3, to which is connected a rod 27 leading to one of the lower shafts of the loom, 75 where it may be actuated to effect rocking movement of the rock shafts.

Mounted on each of the rock shafts 23 for rotative movement therewith is a cam 28, the surface of which is complementary to 80 the surface of the cam 20, and each of the cams 28 is movable longitudinally upon its associated rock shaft; that is, each cam 28 is confined to rotation with its associated rock shaft but has longitudinal movement thereon. As shown in the present instance, each cam 28 is splined to its associated rock shaft 23 by a feather 29, Fig. 4, and a spring 30 interposed between the cam and the collar 31 normally forces the cam 28 into operative engagement with its associated cam 20. As thus far described, it will be apparent that on movement of the bar 25 through its operating means, all of the rock shafts 23 will be given a rocking movement 90 which will be transmitted through the co-operating cams 28 and 20 to the associated vibrator 18.

In accordance with one feature of the 95 present invention, indicators, one for each vibrator, are provided, to indicate the bank of drop wires in which the warp fault has occurred, as will now be explained.

Pivotedly supported upon the bracket 10 and preferably on a transversely extending shaft 32 are a series of indicators 33, the lower end portions 34 of which extend into a circular groove 35 formed on the hub portion of the cam 28, the construction being such that should any one of the vibrators 18 be arrested in its oscillatory detecting movement by a fallen drop wire, the cam 28 acting upon the cam 20 will cause the cam 28 to be moved axially of the vibrator 18, or to the left, Fig. 4, against the tension of the spring 30, while the remaining detectors of the series may continue in operation, and such movement of the cam 28 is transmitted to the associated indicator 33, with the result that the bank of drop wires wherein the warp fault has occurred is visually indicated to the weaver by the indicator.

In order that the loom may be stopped when any one of the vibrators 18 is arrested in its oscillatory movement to enable the weaver to piece up the broken end, means are provided to move the dog 6 into the path of the bunter 5 on the occurrence of a warp fault.

Each of the indicators 33 is provided 125 with a laterally projecting toe 36 upon which rests a bar 37 which extends above each one of the toes of the indicators. The bar 37 is connected to a rock shaft 38 carried by the bracket 10, and in the present 130

instance, such connection is made by means of a lug 39, the upstanding end portion 40 of which is opposite the end of the wire 41 in the flexible sheath 9, as indicated in Fig. 3, so that upon occurrence of a warp fault and the consequent arrest of the associated vibrator, the connected indicator will be moved from its normal to an abnormal position, as indicated by dotted lines in Fig. 4, 10 to indicate the bank of drop wires in which the warp fault occurred, and as the indicator is thus moved from its normal to its abnormal position, the associated toe 36 will act upon the bar 37 and cause the upstanding end of the lug 39 to move the flexible wire 41 longitudinally in its sheath to operatively position the dog 6 for actuation by the lay to effect loom stoppage.

The weight of the bar 37 may be sufficient 20 to maintain the parts in normal operative position, as indicated in Fig. 3, but if desired, the spring 42 may be connected to the bar 37 and the bracket 10 to maintain the parts in their normal position during weaving.

From the construction described, it will be apparent that during normal weaving operation, the several vibrators 18 are free to be oscillated in the wide portion of the 30 slots 16 of the associated bank of drop wires and the parts will maintain relation, as indicated in Fig. 3. Should a warp thread break or become too slack for weaving purposes, however, the drop wire will fall and arrest movement of the associated vibrator 35 18, while the other vibrators may continue for a time in operation. On the arrest of the detector 18 as described, the cam 20 will likewise be stopped, and since the cam 28 40 continues in operation through the train of mechanism hereinbefore described, the cam 28 will be moved axially along the shaft 23 and, perforce, move the associated indicator from its normal full line position, Fig. 4, 45 to its dotted line position, to thereby indicate the bank of drop wires in which the warp fault occurred. As the displaced indicator 33 moves to its abnormal position, its toe 36 will act upon the bar 37 and 50 through the flexible wire 41 effect loom stoppage. Thus it will be seen that the weaver has called to his attention the bank of drop wires in which the broken or too slack warp thread is associated, and immediately thereafter the loom will be stopped to enable the weaver to piece up the broken or too slack warp thread.

What is claimed is:

1. In a warp stop mechanism for looms, 60 the combination of two or more banks of drop wires, a vibrator for each bank, means for oscillating the vibrators about their longitudinal axes, give-way connections between each of the vibrators and the operating means permitting the individual stop-

page of the oscillatory movement of any one of the vibrators by a drop wire on the occurrence of a warp fault, and an indicator moved by the give-way device on stoppage of the oscillatory movement of a vibrator 70 by a drop wire to locate the bank of drop wires in which the warp fault occurred.

2. In a warp stop mechanism for looms, the combination of a plurality of banks of drop wires, an oscillatory vibrator for each bank having a cam connected to each vibrator, operating means for the series of vibrators, separate give-way cam connections between said means and each one of the vibrators, and an indicator associated with each 75 one of the give-way cam connections to indicate the bank of drop wires in which the warp fault occurred when any one of the vibrators is arrested by a drop wire.

3. In a warp stop mechanism for looms, a bank of drop wires each of which has an opening provided with a wide and narrow portion, a vibrator extending through said opening and having oscillatory detecting movement in the wide portion of the opening during weaving, a cam secured to the vibrator for movement therewith, means for oscillating the vibrator including a give-way cam, and an indicator actuated by the give-way cam to indicate the location of the 95 warp fault.

4. In a warp stop mechanism for looms, the combination of a plurality of banks of drop wires, a vibrator for each bank, means for oscillating the vibrators including a separate cam secured to each vibrator, a rock shaft for each vibrator having a separate give-way cam, yielding means normally acting to maintain the cam and give-way cam 100 of each vibrator in operative relation with permissive separate movement of the cams, means for imparting rocking movement to the rock shafts, a separate indicator connected to each give-way cam to indicate the bank of drop wires in which the warp fault occurred when a vibrator is arrested by a fallen drop wire, and means for stopping the loom when a vibrator is arrested by a drop wire.

5. In a warp stop mechanism for looms, the combination of a series of drop wires having wide and narrow openings and arranged in a plurality of banks, an oscillatory non-circular vibrator for each bank 115 freely movable in the wide openings of the drop wires during weaving, brackets for supporting the vibrators, an indicator for each vibrator supported on said bracket, means movable axially of a vibrator when it is arrested by a drop wire, connections between said means and the associated indicator to indicate the bank of drop wires in which the warp fault occurred, and stopping means to stop the loom on occurrence of a warp 120 fault.

6. In a warp stop mechanism for looms, the combination of a series of drop wires each having an opening with a wide and narrow portion and arranged in a plurality 5 of banks, a vibrator extending through the openings of each bank of drop wires, means for imparting movement to the vibrators about their longitudinal axes within the wide portions of said openings during weaving, and separate give-way connections between said means and each one of the vibrators constructed and arranged to permit any one of the vibrators to be individually stopped in its movement by a drop wire.

15 7. In a warp stop mechanism for looms, the combination of a series of drop wires having wide and narrow openings and arranged in a plurality of banks, an oscillatory non-circular vibrator for each bank 20 freely movable in the wide openings of the drop wires during weaving, brackets for supporting the vibrators, a separate indicator for each vibrator pivotally supported on said bracket, means associated with each 25 vibrator and movable axially thereof when the vibrator is arrested by a drop wire, connections between said means and the associated indicator to indicate the bank of drop wires in which the warp fault occurred, and 30 stopping means actuated by the displaced indicator to stop the loom on the occurrence of a warp fault.

8. A drop wire bank indicator for warp stop mechanism, comprising a series of indicators, one for each bank of drop wires, a vibrator for each bank having a detecting movement adapted to be arrested on the occurrence of a warp fault, means associated 35 with each vibrator and moved axially thereof when the vibrator is arrested by a drop wire, and connections between the indicators and axially movable means for moving the associated indicator when the vibrator is stopped by a drop wire to indicate the bank 40 of drop wires in which the warp fault occurred.

45 9. A drop wire bank indicator for warp stop mechanism, comprising a series of indi-

cators, one for each bank of drop wires, a vibrator for each bank having a detecting movement adapted to be arrested on the occurrence of a warp fault, cams associated 50 with each vibrator and one of which is moved axially of the vibrator when the vibrator is arrested by a drop wire, and connections between the indicators and the axially movable cam for moving the associated indicator when the vibrator is stopped by a drop wire to indicate the bank of drop wires in which the warp fault occurred.

10. In a warp stop mechanism for looms, the combination of a series of drop wires each having an opening with a wide and narrow portion and arranged in a plurality 65 of banks, a vibrator extending through the openings of each bank of drop wires, means for imparting movement to the vibrators about their longitudinal axes within the wide portions of said openings during weaving, give-way connections between said means and each of the vibrators constructed and arranged to permit any one of the vibrators to be individually stopped in its movement by a drop wire, and an indicator 70 actuated by the associated give-way device to indicate in which bank of drop wires the warp fault occurred.

11. In a warp stop mechanism for looms, the combination of a plurality of banks of drop wires normally supported by the warp threads during weaving, a separate vibrator for each bank of drop wires, means for imparting movement to the vibrators, give-way connections between said means and each one of the vibrators constructed and arranged to permit any one of the vibrators to be individually stopped in its movement by an associated drop wire, and a separate indicator for each bank of drop wires actuated by the associated give-way connection to 85 indicate in which bank of drop wires the warp fault occurred.

In testimony whereof, I have signed my name to this specification.

HARRY A. DAVIS.
